SEWING MACHINE

Kokichi Matsuda, Tokyo, Japan

Application September 29, 1953, Serial No. 27,003

Term of patent 14 years

(Cl. D70—1)

FIG.1.

FIG.2.

FIG. 3.

FIG. 4.

FIG. 5.

To all whom it may concern:

Be it known that I, Kokichi Matsuda, a subject of Japan, residing at city of Tokyo, Japan, having invented a new, original, and ornamental Design for Sewing Machine, of which the following is a specification, reference being had to the accompanying drawings, forming part thereof.

In the drawings

Fig. 1 is a front elevational view of a sewing machine, showing my new design;

Fig. 2 is a plan view thereof;

Fig. 3 is a side view as seen from the left side of Fig. 1;

Fig. 4 is a side view as seen from the right side of Fig. 1; and

Fig. 5 is a rear elevation of the present sewing machine.

I claim:

The ornamental design for a sewing machine, substantially as shown.
